UNITED STATES PATENT OFFICE

ALEXANDER HART, OF NEW YORK, N. Y.

DESIGN FOR A CLOCK FRAME

Application filed February 8, 1930. Serial No. 34,461. Term of patent 14 years.

To all whom it may concern:

Be it known that I, ALEXANDER HART, a citizen of the United States, whose post-office address is 2201 Amsterdam Avenue, New York, county of New York, and State of New York, have invented a new, original, and ornamental Design for Clock Frames, of which the following is a specification, reference being had to the accompanying drawing, forming a part thereof.

Figure 1 is a front view of a clock frame showing my new design; and
Fig. 2 is a side view thereof.

I claim:

The ornamental design for a clock frame as shown.

ALEXANDER HART.
